[57] CLAIM

The ornamental design for the strong arm adhesive spark plug wire bracket, as shown and described.

DESCRIPTION

FIG. 1 is a front elevational view of the strong arm adhesive spark plug wire bracket showing my new design;

FIG. 2 is a rear elevational view thereof;

FIG. 3 is an enlarged left side elevational view thereof;

FIG. 4 is an enlarged right side elevational view thereof;

FIG. 5 is a top plan view thereof; and,

FIG. 6 is a bottom plan view thereof.

The contrasting shading shown on FIG. 6 represents an adhesive material.
